UNITED STATES PATENT OFFICE.

TATE B. POWELL, OF FRENCH BROAD, TENNESSEE.

DOUBLE-SOLE CLIPPER.

Application filed June 4, 1923. Serial No. 643,380.

To all whom it may concern:

Be it known that I, TATE B. POWELL, a citizen of the United States, residing at French Broad, in the county of Cocke, State 5 of Tennessee, have invented certain new and useful Improvements in Double-Sole Clippers; and I do hereby declare the following to be a full, clear, and exact description of the invention, such as will enable others skilled in the art to which it 10 pertains to make and use the same.

This invention has reference to knitting machines used in the manufacture of double-sole hosiery and particularly to means for 15 increasing the productive capacity of such machines at a saving in both labor and material.

The primary object of the invention is to provide a clipper attachment for knitting 20 machines of the character mentioned which operates, at predetermined intervals during the knitting process, to cut out and save the yarn ordinarily left by the double sole finger of the machine. As is well known to those 25 familiar with knitting machines, of this type, the double sole finger leaves a half round of surplus yarn which has to be cut out of the hose and ordinarily goes as waste. The present invention eliminates both the 30 waste and the labor of cutting this surplus yarn by clipping it automatically during the operation of the machine.

With the above and other objects in view, the invention consists broadly in a clipper 35 mechanism arranged to be operated by a series of levers and cams so as to be automatically thrown into and out of operative position, the various elements being so assembled as to permit their application to 40 or removal from the machine in a convenient and easy manner.

The invention further consists in the novel arrangement and combination of the various parts as hereinafter described and as 45 illustrated in the accompanying drawing, wherein;

Figure 1 is an elevation of a portion of a conventional circular knitting machine with the invention applied thereto.

Figure 2 is a vertical section through the machine showing the position of the clipper.

Figure 3 is a top plan view of the same.

Figure 4 is an enlarged elevation of the 55 clipper and the associated portions of the machine, the latter being shown in section.

Figure 5 is a front elevation of the clipper.

Figure 6 is a horizontal section on the line 60 6-6 of Figure 5.

Figure 7 is a view of the detached portions of the clipper.

Figure 8 shows perspective view of the members 29 and 30.

Throughout the following specification, 65 reference is to be had to the drawing in which similar reference characters indicate corresponding parts in all of the figures.

A double sole knitting machine of conventional type is indicated at 1, to the bed 70 plate 2 of which is attached, by screws or other fasteners 3, a flanged vertical guide-thimble 4 of the invention. Extending thru the thimble, and held in position with respect thereto by an adjustable collar 5, is 75 a pushrod 6 to the exposed lower end of which is pivoted the foot piece 7. A spring, 8 having one end suitably anchored to the flange of the thimble and its other end fastened to the adjustable collar 9 of the push-rod, normally holds the pushrod down. The rod is raised at intervals against the tension of the spring by means of a cam 10 fastened on the collar of the main gear wheel 11 of the knitting machine and abutting the 85 foot piece of the rod intermittently as the wheel revolves. The pushrod is thus caused to move up and down.

The invention further embodies a horizontal bracket 12 having one end suitably 90 fastened to the latch ring 13 of the machine and its other end presenting an upwardly disposed arm 14 on which is supported the clipper mechanism hereinafter described. Carried by the bracket 12 is an upstanding 95 arm or support 15 to the upper end of which is pivoted the rocker arm 16. Each end of the rocker arm has secured thereto an abutment block or shoe, as shown at 17 and 18, respectively; the former being disposed for 100 abutment with the upper end of pushrod 6 by which the arm is rocked on its pivot and the latter being engageable with the clipper mechanism for tripping or operating the same.

The clipper mechanism consists of a main

support member having a relatively wide upper portion 19 and a lower narrow portion or shank 20. Centered longitudinally of the wide portion is an integral outstanding guide 21 having a slot 22 opening outwardly thru one side thereof as shown. Elongated slots 23 are also provided in the member on each side of the guide to accommodate the bolts or other fasteners which 5 secure it to the bracket arm 14. The lower corner of the guide is beveled on the outside of the slot to expose the laterally projecting pin 24 of the clamp-and-cutter carrier 25 which extends both above and below the 10 guide, being slidably engaged in the slot thereof. This carrier is normally held in a raised position by a spring 26, one end of which is attached to the pin 24 while the other end is secured to a bolt 27 passing 15 thru the guide and serving to retain the carrier within the slot. The lower end of the carrier is notched at 28 to accommodate the hooks at the upper ends of the clip elements proper. These elements consist, re- 20 spectively, of a cutter 29 and a clamp 30, and work in a slot in a guide member 31 arranged on the shank 20 of the support which member is held in position by a plate or keeper 32 fastened to the shank in the manner shown. The lower end of the cutter 29 is formed with a laterally directed foot 29', having its upper edge sharpened for severing the thread, while the corresponding end 25 of the clamp 30 is formed with a laterally directed foot 30', having its upper edge blunt for cooperation with the lower end of the guide 33, for gripping and holding the thread while said thread is drawn taut over the cutting edge of the foot 29'. When 30 the carrier 25 is forced down, it moves the cutter and clamp down to a sufficient distance to produce a space between the feet 29' and 30' and the lower end of the guide 31. After the double sole thread has made a 35 complete revolution around the ring of needles of the machine, this thread is released and drawn across the ring and into the space between the feet and clamp. As soon as the thread is thus disposed in said 40 space the carrier is released and permitted to rise, under the influence of the spring 26, with the result that the clamp foot 30' draws the thread upwardly against the guide 31, while the foot 29' severs the thread, the 45 movement of the thread being a shearing one with respect to the cutting edge of the knife foot 29'. On the side of the shank 20 there is secured a plate 32 which serves to guide the thread toward the clamp and cutter. 50 When cam 10 has passed foot piece 7, the pushrod descends by its own weight and the carrier 25 is moved upwardly by the contraction of spring 26, carrying with it the clamp and cutter. The clamp 30 moves 55 upwardly pulling the thread into the slot

of guide 31 and holding it, while the cutter 29 operating on the other side of the slot cuts the thread. The operation is so timed that just as the double sole finger of the machine raises the yarn, the cutter and clamp 70 cut and hold it until the finger drops back in action.

In order that the clipper mechanism may be thrown into and out of operation at the proper time, a series of cams 34 of varying 75 dimensions are affixed to the knitting machine drum and a bracket 35 is attached to the knitting machine frame so as to overlie the drum. Arranged above the bracket is a bell crank lever 36 fulcrumed on a pivot fastened to the frame of the machine and having one end connected to a link 37; its other end being secured to a pushrod 38. Pushrod 38 has a slide bearing in bracket 35 and is normally held downwardly in the path of cams 34 by a spring 39. Hence, when moved 80 up by the cams it rocks the bell crank lever and causes the link 37 to be shifted horizontally. The other end of link 37 has a pivoted extension 40 which, in turn, is secured to the foot piece 7 of the main pushrod. When the link 37 is shifted forward by the raising of pushrod 38 it swings the foot piece out of the path of the gear wheel cam 10 and thus renders the clipper mechanism 85 inoperative. The length of time the mechanism remains inactive is governed by the dimensions and spacing of the cams 34 which may be arranged as desired in each particular case. The attachment is ordinarily 90 arranged to begin operating with the double sole just above the heel and stops on heel and toe in the same manner as the double sole finger of the conventional knitting operates on the double sole. 105

Since the attachment works automatically during the operation of the machine to clip the yarn it is obvious that there is considerable saving effected in both labor and material since the separate cutting from the 110 hose of surplus yarn is entirely eliminated and the wastage of the yarn is avoided.

What I claim is:

1. The combination with the cam drum and double sole thread of a knitting machine, 115 of a guide mounted on the machine, a clamp and a cutter slidably supported on the guide in position to receive the thread, means for reciprocating the clamp and cutter including a tappet rod, means carried by the tappet rod for actuation by the said cam drum, and means for moving the first means into and out of position to be actuated by said cam. 120

2. The combination with the cam drums and double sole thread of a knitting machine, 125 of a guide mounted on the machine, a clamp and a cutter slidably supported on the guide in position to receive the thread, means for reciprocating the clamp and cutter includ- 130

ing a tappet rod, means carried by the tappet rod for actuation by one of the cam drums, and means connected with the first means and actuatable by another cam drum 5 for moving said first means into and out of position to be actuated by the first drum.

3. The combination with the cam drums and double sole thread of a knitting machine, of a guide mounted on the machine, 10 a clamp and cutter slidably supported on the guide, means for reciprocating the clamp and cutter to grip and cut the thread, said means including a tappet rod, means on the tappet rod for engagement by a cam drum, 15 and means carried by the last-named means and actuatable by another drum for moving said last-named means into position to be acted upon by the cam drum.

4. The combination with the cam drums

of a knitting machine, of a guide mounted 20 on the machine and disposed adjacent the double sole thread, a clamp and cutter slidably mounted on the guide for movement away from the guide to receive the thread and cooperate therewith to grip and sever 25 the thread, means for moving the cutter and clamp including a reciprocable tappet rod, the rod having a movable section arranged to be engaged by a cam drum, a reciprocable member arranged to be actuated by another cam drum, and connections between the movable section of the tappet rod and the reciprocable member for setting said section in position to be actuated by the first-named cam drum. 30 35

In testimony whereof, I affix my signature.

TATE B. POWELL.
